UNITED STATES PATENT OFFICE.

DANIEL K. MILLER, OF PHILADELPHIA, PENNSYLVANIA.

MASTER-KEY LOCK.

SPECIFICATION forming part of Letters Patent No. 244,759, dated July 26, 1881.

Application filed November 8, 1880. (Model.)

To all whom it may concern:

Be it known that I, DANIEL K. MILLER, a citizen of the United States, residing at Philadelphia, Pennsylvania, have invented certain 5 Improvements in Master-Key Locks, of which the following is a specification.

The main object of my invention is to so construct a master-key lock that a much greater variety in the combinations of the notches is 10 possible than in an ordinary master-key lock, a further object being to increase the security of this class of locks. These objects I attain by the use of two stumps, or a double stump, in connection with the notched tumblers, and 15 by the use, in combination with the stump-carrier, of a locking-bolt having two notches, all as described hereinafter.

In the accompanying drawings, Figure 1 is a view of my improved master-key lock with 20 the cover-plate removed and the bolt retracted; Fig. 2, a view showing the action of the special key in operating the lock; Fig. 3, a view showing the action of a master-key in performing the same duty; Fig. 4, a view showing the bolt 25 projected; Fig. 5, a side view of the bolt detached from the lock; Fig. 6, a detached perspective view of another part of the lock mechanism, and Fig. 7 a view of a modification.

A is the casing of the lock; B, the bolt, and 30 D the tumblers, of which three are shown in the drawings, although greater number than this may be used, if desired. The bolt B slides longitudinally in the case, and the tumblers are hung to a pivot-pin, E, each of said tumblers being acted upon by a spring, F, and having 35 two notches, *a a'*, formed in its rear edge. These notches are so located in respect to the lower edges of the tumblers on which the keys act that the notches *a* will be brought into 40 line by the special key G, and the notches *a'* by the master-key G'; or the reverse of this may be the case, if desired.

Instead of using but one stump on the shank of the bolt for both sets of notches, as usual, 45 my improved lock has two stumps, *m m'*, which, in the present instance, are in the form of projections on a dog, *b*, the latter being pivoted to the short arm of a bell-crank lever, *d*, hung to a pin on the lock-case. The long arm of 50 the lever *d* is furnished with a projecting spring, *e*, which rests upon the stud carrying the pivot-pin E, the tendency of this spring being to

elevate the end of the long arm of the lever, and thereby press the stumps *m m'* firmly against the rear edges of the tumblers, as shown 55 in Figs. 1 and 4. When the bolt is retracted and the tumblers are down, as shown in Fig. 1, the long arm of the lever *d* occupies a position in a notch, *f*, in the upper edge of the shank of the bolt B, and prevents the projection of said bolt. When the tumblers are acted upon by the special key G of the lock the notches *a* of the tumblers are brought into line with each other and into the path of the stump *m*, which enters the notches, as shown in Fig. 65 2, and thereby allows such a movement of the lever *d* that the end of the long arm of the latter is freed from the notch *f* and the projection of the bolt by the key is permitted. The same movement of the lever *d* takes place on 70 the operation of the tumblers by the master-key G'; but in this case the notches *a'* of the tumblers are brought into line with each other and into the path of the stump *m'*, which enters the notches, as shown in Fig. 3. When the bolt 75 has been projected, either by the special key G or master-key G', a notch, *g*, in the upper edge of the shank of the bolt, is brought into the path of the end of the long arm of the lever *d*, by which means the descent of the 80 tumblers, under the action of the spring F, is permitted, the inclined notches in the tumblers forcing out the stump, and thus causing the pivot of the dog *b* to move rearwardly, the end of the long arm of the lever *d* entering the 85 notch *g* of the bolt, as shown in Fig. 4. I thus overcome an objection to that class of master-key locks in which a stump on the bolt enters notches in the tumblers when the latter are 90 adjusted by the key and remains therein while the bolt is projected, thus retaining the tumblers in their elevated positions, so that by means of a sectional key introduced into the lock the relative positions of the tumblers can be readily determined and a false key for the 95 lock constructed.

In my improved lock the tumblers are not confined by the stump, except during the actual movement of the bolt as the latter is being retracted or projected. Pressure upon the end 100 of the bolt when the latter is projected causes such a retention of the long arm of the lever *d* as to prevent the elevation of the latter by the action of the spring *e*, the stumps *m m'*

being thus prevented from entering the notches in the tumblers, so that any attempt to ascertain the position of said notches by manipulating the tumblers while longitudinal pressure is exerted upon the bolt is effectually prevented.

In an ordinary master-key lock having a single stump, both the special-key notch and the master-key notch have to be formed in the edge 10 of the tumbler, within the limits of the travel of said edge; and, as this space is necessarily contracted, the number of different combinations of special-key notches which can be made is correspondingly limited. By the use of two 15 stumps, however, I am enabled to separate the special-key notches from the master-key notches to any extent desired, and can thus devote to the formation of the special-key notches alone a space equal to the travel of the edges 20 of the tumblers in which said notches are made, thus greatly increasing the number of different combinations attainable.

Different combinations of master-key notches may also be made without interference with 25 the special-key notches, so that with, say, a thousand locks, each requiring a special key differing from those of the others, there may be but one master-key for the entire number 30 of locks, or there may be a number of different master-keys, each controlling but a limited number of locks.

In carrying out my invention, the particular methods of construction before described, and shown in Figs. 1 to 6 of the drawings, need not 35 be adhered to in all cases. For instance, in Fig. 7 I have shown a modification in which sliding tumblers take the place of the pivoted tumblers D. The notched tumblers and double stump may also be used in connection with 40 locks of the character shown in my Patent No. 143,831, October 21, 1873; and in some cases the dog b may be carried by a sliding

plate instead of by a lever, or a central pin on the dog itself may be adapted to the retaining-notches in the bolt. The two notches in the 45 bolt-shank may also be used with advantage in connection with a retaining device having but one stump.

I claim as my invention—

1. The combination of the bolt and the 50 notched tumblers of a master-key lock with two stumps independent of the tumblers, one stump being adapted to the notches brought into line by the special key, and the other to the notches brought into line by the master-key, and with devices whereby the entrance of either stump into its notches is caused to release the bolt, as set forth.

2. The combination of the bolt and the notched tumblers of a master-key lock, a dog, 60 b, having two stumps, m m', formed on or secured thereto, and a bolt retaining and releasing device, to which said dog is pivoted, said stump m being adapted to the special-key notches, and the stump m' to the master-key notches, 65 all substantially as specified.

3. The combination of the notched tumblers, the locking-bolt B, having two notches, f and g, and a stump-carrier having a lug or projection adapted to either of the notches f and g 70 of the bolt, as specified.

4. The combination of the notched tumblers, the locking-bolt B, having two notches, f and g, and a stump-carrier consisting of a bell-crank lever, d, one arm of which has a lug or 75 projection adapted to either of said notches in the bolt, as set forth.

In testimony whereof I have signed my name to this specification in the presence of two subscribing witnesses.

D. K. MILLER.
